UNITED STATES PATENT OFFICE.

ALEXANDER X. KENNEDY, OF TYRONE, PENNSYLVANIA, ASSIGNOR TO WILLIAM A. RIDDELL, OF FREDERICK, MARYLAND.

PAPER-MILL PUMP.

Application filed December 15, 1923. Serial No. 681,000.

My invention relates broadly to the manufacture of paper and like products, and more particularly to a pump for moving the paper stock in a paper mill at the same time that the pulp is mechanically beaten.

One of the objects of my invention is to provide a single bearing paper mill pump arranged to impart movement to the paper stock through the mill independently of gravity feeding of the stock, eliminating the entraining of air with the pulp which has a tendency to impede the progress of the stock.

Another object of the invention is to provide a paper mill pump construction by which heavy stock may be successfully moved through the mill.

A further object of the invention is to provide a paper mill pump with a pair of driving members, one serving as an impeller to centrifugally act upon the stock and another serving as a propeller and a mechanical beater positioned at such a distance from the impeller that a constant mass of paper stock is continuously forced into the eye of the impeller without the entraining of air.

Still another object of my invention is to provide a single suction paper mill pump for handling relatively heavy paper stock in which a plurality of mechanical beaters and propellers may be operated in the suction line in combination with the impeller for treating the stock simultaneously with its movement through the mill.

Other and further objects of my invention will be understood from the specification hereinafter following by reference to the accompanying drawings, in which:

Figure 1 is a diagrammatic view showing the arrangement of my paper mill pump in a mill; Fig. 2 is a front elevation of the pump as arranged in Fig. 1, the suction pipe being broken away to show the propeller and mechanical beater therein; Fig. 3 is a vertical cross sectional view through my pump construction taken on line 3-3 of Fig. 1; Fig. 4 is a cross sectional view through the suction pipe taken on line 4-4 of Fig. 3 showing the propeller used in my pump; Fig. 5 is a side elevation partially in cross section of a modified construction of my paper mill pump having an outboard bearing and a plurality of propellers and

mechanical beaters in the suction line; Fig. 6 is a theoretical diagram illustrating the character of feed motion imparted to the paper stock by my pump construction; and Fig. 7 shows my invention applied to a double suction paper mill pump.

Heretofore in the art much difficulty has been experienced in handling heavy paper stock in a paper mill. Relatively high head of inconvenient proportions has been required to insure delivery of the pulp to the pump. In some installations the location of an elbow in the delivery line, necessary by reason of local convenience, has caused substantial reduction in the flow of the stock when using pumps having the inherent limitations of those heretofore available. In other instances the pump has been necessarily mounted in an inconvenient position out of normal to enable a more direct feed line for the stock to the pump. However, with all these arrangements it has been impossible to successfully employ very heavy paper stock.

By my present invention I am enabled to operate with paper stock as heavy as seven percent. I provide a pump comprising a casing having a single bearing at one side and a suction pipe at the other side; a shaft is journaled in the bearing and extends into the suction pipe. An impeller is carried by the shaft within the casing, and adjacent the extremity of the shaft I provide one or more propellers spaced at a predetermined distance from the impeller within the suction line. Paper stock has many peculiar characteristics, among which are the infinitesimal size of the individual particles which comprise the pulp. These infinitesimal particles are packed compactly and form a semi-plastic body in combination with water. The propeller in my pump construction operates to force this mass of material into the eye of the impeller which in turn imparts centrifugal force to the stock for conveying it forward through the mill. It often occurs that air is entrained with the stock in such manner that the impeller operates only upon an air pocket and the flow of the stock ceases. The propeller in my construction agitates the paper stock, subdividing the infinitesimal particles and delivering them in a horizontal column equal to the distance between the propeller

and the impeller, and forcing the stock into the eye of the impeller. The propeller tends to continually build up this column into a compact mass while the impeller operates to continuously reduce the length of the column as the stock moves forward. It will be observed that a column of stock of substantially constant length is continuously maintained between the impeller and the propeller, insuring constant feed.

As heretofore pointed out, a plurality of beaters and propellers may be operated in the suction line simultaneously with the rotation of the impeller, in which case the stock is positively forced into the impeller at the same time that the particles are subjected to a beating action finely subdividing the same. In this modification an outboard bearing is provided on the drive shaft.

Referring more particularly to the drawings, the pump is shown arranged in the paper mill in Figs. 1 and 2. Reference character 1 indicates the pump casing provided with a suction pipe 2 at one side and a single bearing 3 at the opposite side in which the pump shaft 4 is journaled and driven from a suitable pulley 5 journaled in bearings 6 and 7. The pump and journals are mounted on base 8. The suction pipe 2 is connected through pipe 9 with chest 10 containing the paper stock. A discharge pipe 11 is provided at the opposite end of the pump casing 1 and is arranged to convey the paper stock through pipe 12 passing up through partition 14. The stock is delivered through pipe 15 to the beater 16.

In Fig. 2 the suction pipe has been broken away to show the propeller 17 on the shaft 4. This propeller 17 is keyed upon the shaft 4 as indicated at 18 and secured against axial movement by means of cap nut 19. An impeller 20 is keyed on shaft 4 as indicated at 21 and abuts against shoulder 22 on shaft 4. Vanes 23 are carried by the impeller and arranged to discharge the paper stock into the pump casing 1. The propeller and the impeller are spaced apart on shaft 4 by means of a sleeve 24 at such a distance that a column is provided in which the paper stock is continuously built up by the operation of propeller 17 while impeller 20 tends to continuously diminish the column of paper stock within the area indicated by reference character 25. The suction pipe 2 is provided with a removable hand hole cover 26 adjacent the propeller to enable repairs to be readily made. The casting comprising the suction pipe 2 is continued in a vertical plane forming a wall 27 of the pump casing, the opposite wall of which is completed by casting 28 which supports the single bearing for the pump.

In Fig. 5 I have represented an extension shaft 29 coupled to shaft 4 by means of coupling 30. This shaft is supported in an

outboard bearing 31 and may pass through elbow 32. The pipe section 33 is interposed between the suction pipe 2 and the elbow 32. Positioned at predetermined intervals along the shaft section 29 I may provide propellers 34, 35, 36, and 37 with baffles 38, 39, and 40 positioned in staggered relationship therebetween.

Referring to the theoretical diagram shown in Fig. 6 of the drawings, it will be observed that the heavy paper stock 41 moves through the suction pipe in a compact mass by virtue of the beating action imparted to the stock by the propeller which operates to finely divide the stock and push the same forward into a compact column 42 which is substantially the distance between the propeller and the impeller. The impeller operates to draw the stock forward as indicated at 43 and 44 and diminish the length of the column 42 at a rate proportional to the speed at which the propeller tends to build up the column 42. By this continuous beating action the air pockets in the stock are avoided, for the material is well agitated, and a very heavy stock may be moved forward through the mill.

In Fig. 7 I have shown an application of my invention to double suction pumps. The shaft 4 is journaled at 45 and 46 passing through packing 47 and 48 into pump casing 1. The impeller 20 is centrally mounted on shaft 4 in the pump casing 1 and a propeller 17 and 49 provided at each side thereof in each of the suction pipes. These propellers operate to build up a column of paper pulp on each side of the impeller as heretofore explained in connection with the single bearing construction.

While I have described my invention in certain particular embodiments, it is to be understood that modifications may be made and that I intend no limitations upon the invention other than are imposed by the scope of the appended claims.

What I claim and desire to secure by Letters Patent of the United States is as follows:

1. In a system for forcing paper stock through a paper mill, the combination with a paper mill of a casing, a rotatable shaft, a single bearing in one side of said casing for said shaft, a suction pipe in the opposite side of said casing, an impeller carried by said shaft within said casing, a combined propeller and paper mill pulp beater carried by said shaft adjacent its extremity, said combined propeller and paper pulp beater being spaced from said impeller in such manner that paper stock is formed in a compact column between said impeller and said propeller, said column being continuously diminished at one end by said impeller at a rate proportional to the speed at which it is built up at the other end by oper-

- ation of said propeller whereby said paper stock is continuously moved through the mill.
2. A system for forcing paper stock through a paper mill, comprising in combination with a paper mill a casing, a rotatable shaft, a journal in one end of said casing for said shaft, a suction pipe extending into the other end of said casing, an impeller carried by said shaft within said casing, and a combined propeller and paper pulp beater mounted adjacent the extremity of said shaft in said suction pipe at a distance spaced from said impeller whereby the paper stock is beaten by said propeller and delivered in compact form to said impeller upon rotation of said shaft and passed through the mill.
3. In a system for handling paper stock, the combination with a paper mill of a rotary shaft, a pump casing, a single bearing for said shaft in one end of said casing, a suction pipe in the opposite end of said casing, an impeller carried by said shaft within said casing, and paper pulp beater propeller mounted adjacent the extremity of said shaft within said suction pipe and spaced from said impeller in such manner that paper stock is simultaneously pushed and pulled through the mill with the particles thereof finely divided and the air excluded therefrom by operation of said propeller prior to their passage through said impeller whereby a constant flow of paper stock through said mill is secured.
4. A system for forcing paper stock through a paper mill comprising in combination with a suction pipe a drive shaft extending therein, a centrifugal pump, an impeller for said centrifugal pump positioned directly upon said drive shaft and a propeller mounted on said drive shaft in spaced relation to the eye of said impeller for agitating and beating the stock, liberating air therefrom, rendering it of uniform consistency and simultaneously driving it into the eye of the impeller of the pump.
5. The method of treating paper stock which consists in advancing the said stock through a conduit, simultaneously beating the stock in the said conduit to finely divide the particles thereof and exclude air pockets therefrom, thereafter forming the finely divided particles into a compact mass, and driving it into the eye of the impeller of a centrifugal pump.

In testimony whereof I affix my signature.
ALEXANDER X. KENNEDY.
